(57) CLAIM

The ornamental design for a bed, as shown and described.

DESCRIPTION

FIG. 1 is a left front perspective view of a bed, showing our new design;

FIG. 2 is a front view thereof; and,

FIG. 3 is a left view thereof.

The dash-dot lines in the figures represent portions of the bed that form no part of the claimed design. The dash-dot broken lines in the figures illustrate unclaimed boundaries of the claimed design and form no part of the claimed design. As used herein, the term “bed” may refer to a headboard, a footboard, or a combination of a headboard and a footboard, or a combination of a headboard, a footboard, and side rails connecting the headboard and footboard.
